UNITED STATES PATENT OFFICE.

HARRY J. SIBLEY, OF DAYTON, OHIO, ASSIGNOR TO OHMER FARE REGISTER COMPANY, OF DAYTON, OHIO, A CORPORATION OF NEW YORK.

FARE BOX.

Application filed March 5, 1923. Serial No. 622,934.

This invention relates to boxes or receptacles for the collection of fares or admissions to places of amusement of the type of which coins or tokens are dropped by the 5 passenger or patron into a glass hopper and fall on to a plate where they may be inspected, and upon movement of said plate are deposited in a locked receptacle or cash box. The coins are thus entirely out of the 10 control of the attendant from the time they are dropped into the box by the passenger. It is customary in most cases to provide a cash box which may be removed from the hopper in a closed and locked condition and 15 so taken to the office of the treasurer or other officer who possesses the key necessary to open same.

One object of this invention is to provide 20 retaining devices for the cash box which are locked in the position in which they hold the cash box and must be released for operation by the operation of a Yale lock.

A further object of the invention is to 25 provide means separate from the said Yale lock for operating the cash box retaining devices after they have been released for operation.

A further object of the invention is to 30 provide a positively actuated lock for the cash box cover in place of a spring actuated lock.

A further object of the invention is to 35 provide a movable handle for operating the cash box cover and means whereby the removal of this handle actuates the lock to positively lock the cash box.

A further object is to provide means for 40 preventing the removal of the cash box until the operating handle has been removed, and for preventing the removal of the operating handle until the cash box cover has been opened to drop into the box any coins upon the cover, and then closed so that the positive lock may become effective on removal of the handle.

A further object is to provide means under 45 the control of the Yale lock for preventing the removal of the handle until the cash box retaining devices have been unlocked.

In the accompanying drawings:

Figure 1 is a side elevation of so much of 50 the fare box as is necessary to show the present invention, certain parts of the frame being broken away for greater clearness.

Figure 2 is a perspective of the cash box

cover and the frame by which it is attached to the cash box, the bottom plate of the cover which protects the mechanism from dust and mechanical injury being removed to show the operation of said mechanism. 60

Figure 3 is a plan view of the cash box and its cover.

Figure 4 is a perspective of a portion of the cash box, showing the relation thereto of 65 the operating handle.

Figure 5 is a perspective of the cam and a portion of the locking plate which controls the positively operated locking slide.

The coin hopper 6 is fixed by any desirable means to a base 7 which forms an inwardly extending top flange on the square frame 10 which contains the devices for retaining the cash box in position and releasing said cash box when desired. The frame 10 supports the apparatus from a pedestal 75 by any suitable attaching means, one form of which is indicated at 11. The walls of the cash box are indicated generally by 12, the cash box being inserted in the frame 10 from below and being guided into position by 80 springs 13 of which there are two extending inwardly from each of the four walls of the frame 10. Near the top of two opposite walls of the cash box are riveted two metal plates 14 which form a part of the cash box 85 holding means. The ends of these plates are engaged by shoulders on two pairs of arms 15 and 151, which pairs of arms are respectively mounted on spindles 16 and 161 which are supported in the walls of the frame 10. 90

The arms 15 and 151 are connected to move inwardly and outwardly together by means of a link 17 connected to the arm 151 at 152 and to an extension 18 of the arm 15. The spindle 16 extends through one of the walls 95 10 and carries a thumb piece 20 for the operation of these retaining devices. The retaining devices are pressed toward retaining position by a spring 19 extending between opposite arms 15 and 151. A lateral extension 100 from the link 17 terminates in a horizontal extending portion 21 which lies adjacent the bolt 22 of a Yale lock so that the retaining devices can be operated only when the bolt 22 is retracted.

The cash box cover is indicated generally by 25 and is carried by a frame 26 which is fixed to the top of the cash box by any suitable means. In the present instance ears 27 extend downwardly from the frame adj- 110

cent the walls of the cash box and receive rivets extending through said walls. A bar 28 is suitably attached to the cover 25. The ends of this bar form trunnions which find 5 a bearing in brackets 30 attached to the frame 26. The cover is pressed toward closed position by spring 29 upon a rod 301 supported from the walls of the cash box and engaging said cover. The bar 28 is 10 provided with a longitudinal slot 280 which receives the removable operating handle 31. This handle comprises notches and lugs which are so related to the openings in the cash box walls through which it must pass 15 that a movement of the cover from closed position to extreme open position and back again to closed position is necessary to either insert or withdraw the handle. For this purpose the wall 12 adjacent the thumb piece 20 282 on the operating handle is provided with a horizontally elongated opening 287, and the wall opposite the thumb piece is provided with an upwardly elongated opening 285, as shown in Figure 4. The handle may 25 thus be inserted through the adjacent wall only when in a horizontal position, and through the opposite wall only when in an inclined position, in which position the cash box cover is open. When the handle is in 30 operating position reduced portions 283 and 284 are opposite the walls of the cash box and permit the operating handle to turn.

Provision is made for preventing the removal of the operating handle until the bolt 35 of the Yale lock has been retracted to permit the operation of the cash box retaining devices to release the cash box. For this purpose a bell crank 33-34 is pivoted on spindle 161. The arm 33 of this bell crank 40 is in engagement with the tongue 22 of the Yale lock, the bell crank being held in this position by means of spring 35, one end of which is held by a stud on the wall 10. The arm 34 of the bell crank is adapted to engage 45 a groove 36 in the operating handle adjacent the thumb piece. The spring 35 moves this arm to unlocking position when the tongue 22 of the Yale lock is retracted.

A slide 37 for locking the cash box cover 50 extends transversely of the bar 28 and is supported from the operating plate 25 of the cash box cover on studs 38 passing through slots in said slide. The slide is 55 designed to be positively operated when the operating handle is withdrawn. For this purpose a one-way pawl 39 is pivoted on a stud 40 on the end of slide 37 adjacent to the operating handle. This pawl has a bevelled end 391 which is upturned in such a 60 manner as to engage the end of slide 37 and prevent the pawl rocking when it is engaged by the operating handle as it is withdrawn. On the handle being inserted, however, the pawl rocks idly on its pivot. A spring 41 65 tends to hold the pawl in operative position.

The pawl 39 extends through a lateral slot 42 in the bar 28 and into the path of the operating handle. When the handle is in operating position this pawl lies in a slot 43 in the handle, but when the handle is withdrawn, the pawl engages a cam surface 44 and the pawl together with the locking slide 37 on which it is mounted, is forced outward. The opposite end of the slide 37 engages a slot 45 in a plate 46 extending 75 downward from the frame 26.

The locking slide 37 is spring pressed toward ineffective position by means of a spring 47 mounted on a stud 48 on the plate 25 and engaging a stop 49 on the locking side; hence provision must be made for securing the slide 37 in locking position. For this purpose the locking slide is provided with a shoulder 50. When the slide 37 is in forward position, a tongue 51 of a spring 80 lock indicated generally by 52 engages shoulder 50 retaining slide 37 against being withdrawn from slot 45 by its spring 47. The key which unlocks lock 52 is kept in the office of the cashier or some other responsible official of the company so that the box is positively locked against being opened until it is in the hands of such official. An altogether different key unlocks 85 the Yale lock which permits the box to be removed from the frame 10.

It has been found in practice that the opening in the wall 12 of the cash box, which is designed to permit the operating handle to be withdrawn only when the cover is closed and in position to be locked, becomes worn to such an extent as to permit the withdrawal of the operating handle while the slide 37 is entirely out of reach of the plate 46; hence the handle can be removed and the cash box also removed without the cover being closed and locked. In the present invention provision is made for overcoming this difficulty. A plate 53 is mounted on the cover 25 by means of studs 54 100 and is spring pressed toward the right in Figure 2 by spring 55. A downturned end 531 of plate 53 engages a notch 56 in the locking slide 37. To withdraw the end 531 105 from notch 56, and permit the operation of the slide to locking position, a cam 58 is placed on the frame 26. The arrangement is such that plate 53 will be moved to the left by cam 58, a sufficient distance to permit the operation of the locking slide when, and only when the cover is entirely closed and in position to be locked.

In order to remove the cash box from the frame 10, the following operations are necessary in the order named.

First, a Yale key must be inserted in lock 23 and turned to retract the bolt 22. This operation permits spring 35 to rock bell crank 33-34, withdrawing arm 34 from the notch 115 in the operating handle. The cover is then 120

- turned to open position, dropping into the cash box any coins retained thereon. In this position the slot in wall 12 permits the operating handle to be withdrawn until it is clear of this wall. About this time shoulder 286 engages the opposite wall 12 preventing the handle from being withdrawn further while the cash box cover is open. The cover must then be closed; when slot 287 permits the operating handle to be entirely withdrawn. On closing the cover the locking end 351 of plate 53 is moved out of engagement with slide 37 by the action of cam 58. On further withdrawal of the operating handle the cam 44 engages pawl 39, and moves the slide 37 into engagement with slot 45. The tongue 51 of lock 52 engages shoulder 50, locking slide 37 in said position. The handle being entirely withdrawn, the cash box retaining arms 15 and 151 are removed to ineffective position by means of thumb piece 20 and the closed and locked cash box removed.
- The invention is not to be construed as limited to the specific form herein described and illustrated in the drawings, but is to be understood to include any variations within the scope of the appended claims.
- I claim:
30. 1. A fare box closing device comprising a frame, a cover hinged to said frame, a locking slide carried by said cover, a co-operating notched plate carried by said frame, a spring pressing said locking slide toward ineffective position, a spring pressing said cover toward closed position, an operating handle for said cover, and means associated with said handle for moving said lock to effective position.
  35. 2. A fare box closing device comprising a hinged cover, a locking slide supported on said cover, an operating handle for said cover, means whereby a movement of said handle actuates said slide, and means controlling said movement.
  40. 3. A cash box closing device comprising a hinged cover, a locking slide for said cover, a removable operating handle, and means whereby the removal of said handle effects movement of said locking slide to locking position.
  45. 4. In a fare collection device, a frame comprising a coin receiving hopper, a cash box adapted to be inserted into said frame, a cover hinged to said cash box, operating means for said cover insertible into said cover thru openings in said frame, and means whereby the removal of said operating means effects the locking of said cover.
  50. 5. In a fare collection device, a frame comprising a coin receiving hopper, a cash box adapted to be removably held in said frame, a cover connected with said cash box, an operating device for said cover adapted to be inserted into and removed
  55. from said cover while said cash box is in place in said frame, and means whereby removal of said operating device effects the locking of said cover in closed position.
  60. 6. A cash box provided with a covering device fitting within the walls of the box, removable operating handle for said covering device extending thru said walls and said covering device, and means preventing removal of said handle until said covering device has been first opened and closed.
  65. 7. In a fare collection device, a frame comprising a coin receiving hopper, a cash box adapted to be removably held in said frame, a cover connected with said cash box, and a removable operating handle for said cover insertible thru a slot in said cover and thru openings in said frame.
  70. 8. A cash box provided with a cover fitting within the walls of the box, and removable operating handle for said cover passing thru openings in opposite walls of the box, and thru a slot in said cover, one of said openings preventing withdrawal of said handle until the cover has been fully opened, the other of said openings preventing withdrawal of said handle until the cover has been fully closed.
  75. 9. A cash box provided with a cover, a removable handle for controlling said cover, and means preventing the removal of said handle until said cover is closed and locked.
  80. 10. A cash box provided with a cover, a lock for said cover, an insertible handle for controlling said cover, and means for preventing the insertion of said handle while the cash box cover is locked.
  85. 11. An operating handle for a cash box closure provided with reduced portions permitting rotation of said handle when in operative position, enlarged portions for locking purposes, and a lateral recess terminating in a cam surface.
  90. 12. A cash box closure comprising a cover, a longitudinally recessed bar in said cover, a removable operating handle adapted to occupy said recess, and locking devices carried by said cover and actuated by said handle.
  95. 13. A cash box closure comprising a cover, a handle insertible in said cover, a locking slide carried by said cover, and means whereby the withdrawal of said handle effects movement of said locking slide.
  100. 14. A cash box closure comprising a cover, a handle insertible in said cover, a slide for locking said cover in closed position, and means whereby the longitudinal movement of the handle operates the slide to locking position, said means being effective to operate said slide on movement of the operating handle in one direction only.
  105. 15. A cash box closing device comprising a cover, a handle insertible into said cover, a locking slide for locking said cover in

closed position, a pawl pivoted on said slide, a cam surface on said handle operative on said pawl, said pawl being effective on movement of said handle in one direction 5 to move said locking slide longitudinally.

16. A cash box closing device comprising a cover, a handle insertible in said cover, a lateral recess in said handle terminating in a cam surface, a slide for locking said cover 10 in closed position, a pawl pivoted on said slide, a stop preventing turning movement of said pawl in one direction a spring holding said pawl normally against said stop and in the path of movement of said handle, 15 whereby said pawl is rocked on its pivot in one movement of said handle, and acts to thrust said slide outward in the reverse movement of said handle.

17. A cash box closing device comprising 20 a cover, an operating handle insertible into said cover, a recess in said handle terminating in a cam surface, a locking device, a pawl associated with said locking device and occupying said recess when said handle is in 25 operative position, said pawl being effective on movement of said handle in one direction to operate said locking device.

18. A cash box closing device comprising a cover, an operating handle insertible in 30 said cover, a recess in said handle terminating in a cam surface, a locking device, a pivoted pawl associated with said locking device and projecting into the path of movement of said handle, a stop preventing movement of said pawl in one direction from its 35 normal position, whereby on inserting said handle said pawl is rocked idly about its pivot, in the operating position of said handle said pawl rests in normal position in 40 said recess, and on withdrawal of said handle, said pawl by engagement with said cam surface, actuates said locking device.

19. A cash box closure comprising a cover, an operating handle insertible in said cover, 45 and means contained in said cover for preventing removal of said handle when said cover is not in closed position.

20. A cash box closure comprising a cover, an operating handle insertible in and re- 50 movable from said cover, a locking device adapted to be moved to locking position, by said handle on its withdrawal, and means inhibiting the movement of said locking device when said cover is not in closed position.

55. 21. A cash box provided with a cover, a lock for said cover movable relative thereto, to effect locking thereof, positive means normally inhibiting the movement of said lock 60 to effective position, and means normally rendering said inhibiting means ineffective when said cover is in closed position.

22. A cash box provided with a cover, a locking slide for said cover, a notch in said 65 slide, a retaining slide having a portion nor-

mally in engagement with said notch, and a cam on said box adapted to withdraw said retaining slide from said notch when said cover is in closed position.

23. A cash box locking device comprising 70 a locking slide, a retaining slide for positively preventing the movement of said locking slide from unlocked position, means for moving said retaining slide to inoperative position, means for positively moving said locking slide to locking position, and means for positively retaining said locking slide in locking position.

24. A cash box locking device comprising 80 a locking slide, a retaining slide for positively retaining said locking slide in unlocked position, means for moving said retaining slide to ineffective position, and means for positively moving said locking slide to locking position, both said means being normally ineffective, and being simultaneously rendered effective.

25. A cash box closure comprising a hinged cover, a locking slide adapted to lock 90 said cover in closed position, a retaining slide normally preventing movement of said locking slide, a device for positively actuating the locking slide but normally incapable of the requisite movement, means for moving said retaining slide to ineffective position, and means releasing said device for lock actuating movement, both said means becoming effective when said cover is moved to closed position.

26. A cash box closure comprising in combination a cover, a locking slide adapted to be positively actuated toward locking position, a spring pressing said locking slide toward unlocked position, a retaining slide normally holding said locking slide in unlocked position, means effective when said cover is closed for moving said retaining slide to ineffective position, means for actuating said locking slide when said cover is in closed position, and means for retaining said locking slide in locked position against the tension of its spring.

27. A cash box closure comprising a cover 105 spring pressed toward closing position, a positive lock for said cover, an operating handle for said cover capable of both rotary and longitudinal movement, means whereby said rotary movement opens said cover against the tension of its spring, and means whereby longitudinal movement actuates said positive lock.

28. A cash box closure comprising a cover 115 spring pressed toward closing position, a positive lock for said cover, an operating handle for said cover capable of both rotary and longitudinal movement, means whereby said rotary movement opens said cover against the tension of its spring, and means whereby longitudinal movement in one direction actuates said positive lock, and 120 125 130

means for preventing the necessary longitudinal movement except when the cover is in closed position.

29. A cash box provided with a closure comprising a cover, a lock for said cover and a removable operating handle, said handle being adapted on rotation to open said cover and adapted on withdrawal to actuate said lock, a shoulder on said handle adapted by contact with a wall of said box to prevent the initial withdrawing movement of said handle until said cover is fully opened, a slot in said wall permitting the passage of said shoulder when said cover is fully opened, a second shoulder on said handle engaging a second wall of said box after the initial withdrawing movement to prevent further withdrawal of said handle, a slot in said second wall permitting the passage of said second shoulder when the handle is turned so that the cover is closed, and a cam on said handle effective as said handle is further withdrawn to actuate said lock.

30. A cash box provided with a closure comprising a cover, a lock for said cover, and a removable operating handle for opening and closing said cover, a shoulder on said handle adapted by contact with a wall of said box to retain said handle in operating position, a slot in said wall to permit withdrawal of said handle from said wall when said handle and cover are in one certain position, a second shoulder on said handle adapted by contact with a second wall of said cash box after said handle has been withdrawn clear of said first wall to prevent further withdrawal of said handle while in the position in which it can pass thru said first wall, a slot in said second wall which permits complete withdrawal of said handle only in a second position different from the position in which it can pass the first wall.

31. A cash box provided with a closure comprising a cover, a lock for said cover and a removable operating handle, said handle being adapted on rotation to open said cover and adapted on withdrawal to actuate said lock, a shoulder on said handle adapted by contact with a wall of said box to prevent the initial withdrawing movement of said handle until said cover is fully opened, a slot in said wall permitting the passage of said shoulder when said cover is fully opened, a second shoulder on said handle engaging a second wall of said box after the initial withdrawing movement to prevent further withdrawal of said handle, a slot in said second wall permitting the passage of said second shoulder when the handle is turned so that the cover is closed, a cam on said handle effective as said handle is further withdrawn to actuate said lock, a

retaining device positively preventing movement of said lock and means disabling said retaining device when said cover is in closed position.

32. A fare box comprising a separable coin receiving hopper, and cash box, said cash box comprising a cover which forms a bottom for said hopper, a removable handle for operating said cover, and means preventing the separation of said cash box and hopper while said handle is in operating position.

33. A fare box comprising a hopper rigidly attached to a base frame, a cash box adapted to be inserted in said frame into position to receive articles deposited in said hopper, a cover for said cash box on which articles deposited in said hopper are retained for inspection, a spring pressing said cover to closed position, a removable operating handle for said cover, and means whereby the removal of said handle effects the locking of said cover in closed position.

34. A fare box comprising a hopper rigidly attached to a base frame, a cash box adapted to be inserted in said frame into position to receive articles deposited in said hopper, a cover for said cash box, on which articles deposited in said hopper are retained for inspection, a spring pressing said cover to closed position, removable operating handle for said cover, and means whereby removal of said handle locks said cover in closed position, and a device associated with said frame normally preventing the removal of said handle.

35. A fare box comprising a hopper rigidly attached to a base frame, a cash box insertible in said frame, a cover for said cash box on which articles deposited in said hopper are retained for inspection, an operating handle for said cover insertible, and removable thru an opening in said frame, a device associated with said frame for preventing the insertion of said handle thru said opening, and key controlled means, for rendering said device ineffective.

36. A fare box comprising a hopper rigidly attached to a base frame, a cash box insertible in said frame, a cover for said cash box on which articles deposited in said hopper are retained for inspection, an operating handle for said cover insertible and removable thru an opening in said frame, a lever pivoted to said frame, a recess in said handle adapted to receive a part of said lever, a spring pressing said lever away from said recess, and key controlled means for removing said lever toward said recess.

37. A fare box comprising a hopper rigidly attached to a base frame, a cash box insertible in said frame, a cover for said cash box on which articles deposited in said hopper are retained for inspection, an operating handle for said cover insertible and remov-

- able thru an opening in said frame, and key controlled means for retaining said handle in operative position.
38. A fare box comprising a hopper rigidly attached to a base frame, a cash box insertible into said frame, supporting devices fixed to said cash box, cooperating movable supporting devices associated with said frame, and key controlled means for preventing movement of said movable supporting devices.
39. A fare box comprising a hopper rigidly attached to a base frame, a cash box insertible into said frame, supporting devices for said cash box pivoted to said frame and spring pressed toward effective position, a thumb piece for operating said supporting devices, and key controlled means for preventing movement of said supporting means to ineffective position.
40. A fare box comprising a hopper rigidly attached to a base frame, a cash box insertible into said frame, supporting devices for said cash box comprising a pair of spindles pivoted in said frame, arms upwardly extending from said spindles, and a connecting link between opposite arms to cause said arms to move in unison.
41. A fare box comprising a hopper rigidly attached to a base frame, a cash box insertible into said frame, supporting devices for said cash box comprising a pair of spindles pivoted in said frame, arms upwardly extending from said spindles, a connecting link between opposite arms to cause said arms to move in unison, a device associated with said link, and key controlled means acting on said device to inhibit movement of said link and said supporting devices from supporting position.
42. A fare box comprising a hopper rigidly attached to a base frame, a cash box insertible into said frame, supporting devices for said cash box comprising a pair of spindles pivoted in said frame, arms upwardly extending from said spindles, a connecting link between opposite arms to cause said arms to move in unison, a device associated with link, key controlled means acting on said device to inhibit movement of said link and said supporting devices, and manually operable means for moving said supporting devices after said key controlled means has been rendered ineffective.
43. A fare box comprising a hopper, a cash box separable from said hopper, supporting devices for said cash box associated with said hopper, means for moving said supporting devices to release said cash box, a cover for said cash box, a handle for operating said cover, said handle being insertible and removable thru an opening in a part of said hopper, a lock, means controlled by said lock for preventing removal of said handle, and other means controlled by said lock for preventing movement of said supporting devices to releasing position.
44. A fare box comprising a hopper, a cash box separable from said hopper, a cover for said cash box, an operating handle for said cover insertible and removable thru said cover, and thru an opening in a part of said hopper, means whereby the removal of said handle effects locking of said cover, and key actuated means normally preventing the removal of said handle and the separation of said cash box from said hopper.
45. A fare box comprising a hopper, a cash box separable from said hopper, a cover for said cash box adapted when the cash box is in operating position to retain articles placed in the hopper in position for inspection, an operating handle for said cover insertible and removable thru said cover and thru an opening in a part of said hopper, whereby said handle must be removed before said cash box can be separated from said hopper.
46. A fare box comprising a hopper, a cash box separable from said hopper, a cover for said cash box adapted when the cash box is in operating position to retain articles placed in the hopper in position for inspection, an operating handle for said cover insertible and removable thru said cover and thru an opening in a part of said hopper, key controlled means retaining said handle in operating position, means associated with said cash box preventing initiating withdrawal of said handle after said key controlled means has been rendered ineffective until said cover has been opened to deposit articles thereon in said cash box, and other means associated with said cash box for preventing complete withdrawal of said handle until said cover has been closed.
47. A fare box comprising a hopper, a cash box separable from said hopper, a cover for said cash box adapted when the cash box is in operating position to retain articles placed in the hopper in position for inspection, an operating handle for said cover insertible and removable thru said cover and thru an opening in a part of said hopper, key controlled means retaining said handle in operating position, means associated with said cash box preventing initiating withdrawal of said handle after said key controlled means has been rendered ineffective until said cover has been opened to deposit articles thereon in said cash box, other means associated with said cash box for preventing complete withdrawal of said handle until said cover has been closed, and a lock for retaining said cover closed, actuated by said handle on the same being withdrawn.
48. A fare box comprising a separable hopper and cash box, manually operable supporting devices for said cash box, a cover for

said cash box adapted when said cash box is connected with said hopper to retain articles placed in said hopper thereon for inspection, a removable operating handle for said cover, and means whereby separation of said cash box from said hopper requires the insertion and turning of a key, the opening of said cover, the partial withdrawal of said handle, the closing of said cover, the complete withdrawal of said handle, accompanied by a positive locking of said cover, and the normal actuation of said supporting devices.

49. A fare box comprising a separable frame and cash box, and means for supporting said cash box in said frame comprising

projecting parts affixed to the sides of said box, supporting devices adapted to engage said projections, and means for retracting said supporting devices.

50. A fare box comprising a separable hopper and cash box, manually operable supporting devices for said cash box, a cover for said cash box, a removable operating handle for said cover, key controlled means for inhibiting the movement of said supporting devices and the withdrawal of said handle, and means retaining said cash box in engagement with said hopper until said handle is removed.

HARRY J. SIBLEY.
